UNITED STATES PATENT OFFICE

STUART HILDER, OF GLENCAIRN, VIRGINIA, ASSIGNOR TO MONROE CALCULATING MACHINE COMPANY, OF ORANGE, NEW JERSEY, A CORPORATION OF DELAWARE

KEYBOARD FOR REGISTERS

Application filed October 8, 1931. Serial No. 587,635.

The invention relates to clearing means for the keyboards of key set registers, having for its object the provision of means whereby a visual indication of the amount set will remain for the guidance of the operator up to the time that a new amount is set, and whereby the keyboard may nevertheless be automatically cleared. The invention consists in the novel construction and combination of parts, as set forth in the appended claims.

In the accompanying drawings, illustrating the invention:

Fig. 1 is a plan view of a calculating machine constructed in accordance with the invention.

Fig. 2 is a right hand side elevation of the same with the casing broken away.

Fig. 3 is a transverse section through the keyboard.

Fig. 4 is a detail side elevation of the clearing means, shown as applied to a machine in which the keyboard is cleared by depression of a series of zero keys.

Fig. 5 is a right hand side elevation of a calculating machine, with casing broken away, showing the application of the invention to an index dial mechanism.

Fig. 6 is a diagrammatic view illustrating the means for selectively setting the index dials.

Fig. 7 is a rear elevation of the index dial mechanism with the casing in section and parts of the machine removed.

Fig. 8 is a detail right side elevation of the repeat—non-repeat mechanism.

In these drawings, 18 represents the digit keys of a calculating machine, whereby the differential actuating mechanism is set to represent the amount to be registered upon the numeral wheels of the machine upon operation of said actuating mechanism. The keys 18 set the actuators differentially by means of selector bails 19 or by any other

suitable devices. The arrangement here shown is that disclosed in the U. S. patent to E. E. Phinney 1,399,652, issued December 6, 1921, and entitled Setting-up means for calculating machines.

Upon depression from normal raised po-

sition any key 18 will move the related bails 19 to set the actuator in accordance with the value of the key, a spring operated locking bail 6 falling into a notch of the key stem to retain the parts in set position. The keyboard is of the "flexible" type, the locking bails 6 being each common to a row of keys 18 and being moved out of locking engagement with a depressed key by the depression of a second key of the same row. Upon release, the keys are raised into normal position by means of springs 10.

An amount having been set in the keyboard 18, the actuating mechanism is rotated one or more times, to register the amounts set on the keyboard, or a multiple of such amount in the numeral wheels, the keys 18 remaining latched in set position during this operation. Upon depression of any key 18, in setting up a new amount to be registered, means will be operated to automatically release all of the keys 18 from depressed position, this means operating during the first part of the downward movement of the key and not interfering with the latching of said key in depressed position. This means comprises a slide 86 extending transversely of the keyboard and engaging each of the locking bails 6, so that any one of said bails, upon depression of a related key will move said slide endwise, and thereby, through bell crank lever 87, will trip a latch 88 engaging a pawl 89 carried by arm 90, so that said pawl will be moved forwardly under the influence of spring 91 and will contact with one arm of a bell crank lever 26 engaging a second transverse slide 23 and moving said slide against each of the locking bails 6, to rock the same and release the keys 18. Pawl 89, continuing to move forwardly, a cam surface 92 of the pawl will engage a pin 93 fixed in the frame of the machine, and the forward end of said pawl will be lifted out of engagement with bell crank lever 26, so that the locking bails 6 may be returned to normal position under the influence of their springs.

The releasing mechanism remains in this inactive position during the subsequent setting of keyboard 18, the pawl 89 being re-

latched and spring 91 retensioned upon the next rotation of the actuating means. This is accomplished by means of a cam 94 mounted on a rotary part connected with 5 the differential actuators, said cam operating against an arm 95 of lever 90 to move the latter rearwardly and engage the pawl 89 with the spring latch 88.

Preferably, amounts may also be cleared 10 from the keyboard 18 by a manual clearing device, for which purpose the usual clear key 30 may be provided, serving upon depression to rock bell lever 26 and clear the keyboard by means of a lever 36, engaged 15 by the key and engaging the bell lever.

The invention may be applied to a calculating machine constructed in accordance with the disclosure of Patent 1,750,565, issued 20 to E. F. Britten, Jr. on March 11, 1930, and entitled Zero key mechanism for key-set registers.

According to this disclosure the keyboard is cleared by the depression of a series of 25 zero keys 38 (Fig. 4) one for each column of digit keys, the keys 38 cooperating with the locking bails 6 in the same manner as the other keys, and therefore, serving upon depression to release other keys depressed 30 in the respective columns. In this form of the invention, the pawl 89 contacts with a bell crank lever 96, which lever operates an arm 33, forming part of a universal bail 34 lying above the bent ends 32 of the keys 38, so that upon movement of the bell crank lever 96, bail 34 will pull down any of the keys 38 which may be in raised position. This application of the invention allows 35 amounts to be set in the keyboard 18 in 40 such a way that they will not be cleared by the automatic clearing means or by depression of the clear key. This is accomplished by depressing a zero key 38 simultaneously with the depression of a digit key in the 45 same column, thus, the zero key being already depressed, the related bails 6 will not be operated thereby upon movement of the clearing bail 34, and the amount will remain 50 set in the keyboard. This is used in various "double operations", wherein it is desired to retain a constant factor in one part of the keyboard, while changing an amount set in another part of the keyboard.

By the use of the above-described forms 55 of the invention the keyboard clearing means is rendered entirely automatic, operating in every case only when a new amount is to be set on the keys. It will therefore be unnecessary to use the repeat— 60 non-repeat mechanism, provided heretofore in automatically cleared mechanisms, in order to disable the means operable upon each cycle of the actuators to clear the keyboard, and thereby permit multiplication 65 and division to be performed.

There is, therefore, nothing which need be set before beginning an operation, and which the operator must observe in order to secure the desired result. If desired, however, means may be provided for disabling the automatic releasing means, so that the setting will not be cleared upon depression of a key 18. For this purpose a key 97 is shown, this key, by means of a lever 98 operating to hold the forward end of pawl 89 raised out of operative position. Key 97 may either be held depressed while one or more keys 18 are set, or the key 97 may be moved to bring a shoulder 99 thereof under the keyboard plate, whereby the clearing means will remain inoperative until the key 97 is released. Obviously, if desired, key 97 might be made without the shoulder 99, and operated only in the manner first described. 70 75 80 85 90 95 100 105 110 115 120 125 130

The invention may also be used in order to retain an indication of the amount set in the keyboard 18 upon index dials 408 (Fig. 5). In this form of the invention a repeat—non-repeat mechanism would be used, so that the keyboard 18 could be cleared during each cycle of operation of the actuators, without removing the indication of the amount which had been set up and registered.

The setting means, whereby the keys 18, in addition to the adjustment of selector bails 19, will also set the index dials 408, may be in accordance with the disclosure of application #414,142, filed by G. C. Chase and L. R. Brown on December 14, 1929, and entitled Calculating and listing machines, since issued (May 10, 1932) as Patent No. 1,857,356.

In accordance with this disclosure, two slides 400 and 401 lie beneath key stems of each row of keys 18, and are provided with graduated cam lugs whereby one or both of the slides may be moved forwardly from normal position. Slides 400 and 401 are connected by a lever 403, and upon movement of either slide, said lever will fulcrum upon the other slide, to impart a given degree of movement to a locator member 406.

Slide 400 is adjusted to one of four positions, whereby, with slide 401 in normal position, index dial 408 will be moved to register 1, 2, 3 or 4. Slide 401 is moved from normal to a single adjusted position, the locator 406 being thereby moved in the opposite direction, five numeral places to register five. With slide 401 in adjusted position, movement of slide 400 will retract locator 406 toward its median or normal position to register 6, 7, 8 or 9, as will be obvious from inspection of the diagram, Fig. 6.

In moving back and forth, locator 406, by means of the opposed lugs 474, engaging a flange 482 of the related index dial 408, will rock such index dial about its shaft, to bring 130

the appropriate numeral marking under the opening in the keyboard.

During this setting operation, the various index dials 408 will be held in adjusted position by the respective latched down keys 18. Upon operation of the machine, to register the amount, special locking means will be employed to hold the index dials 408 as adjusted, and the keys 18 will be released by means of cam 56 (Fig. 8) fast upon the rotary part of the machine, and engaging a lever 57 and moving the same against the bell lever 26, to rock the locking bails 6, through the slide 23.

15 The index dials 408 are locked by means of a bail 413 engaging serrated portions of the dials, bail 413 having a spring connection 415 with a frame 475, moved by a cam 476 secured upon the rotary shaft of the machine.

20 Cam 476 moves frame 475 against the tension of a spring 477, and engages a part of the frame with a latch 478, whereby the spring is held under tension. Locator 406 has pin and slot connection with frame 475, so that

25 when the frame is moved by cam 476 to engage the locking bail 413, the locators will be moved away from the flanges 482 of the index dials, so that they move independently thereof.

30 Upon setting up the next amount on the keyboard 18, a slide 479, similar to the slide 86, previously described, will be moved endwise, a lower extension 480 of this slide (Fig. 7) operating a lever 481 to release the latch

35 478, whereupon the spring 477 will raise the frame 475 and locking bail 413 will be released from the serrations of the index dials. At the same time, the locators 406, moving upwardly against the flanges 482 will locate 40 the index dials in accordance with the new key setting.

The repeat—non-repeat mechanism may be of any desired construction, one example being shown in Fig. 8, wherein a non-repeat 45 key 58 serves to move the lever 57 out of the path of cam 56, so that no automatic clearing impulse will be received.

It may be noted that when this non-repeat mechanism operates, slide 23 moves the key 50 locking bails 6, these bails in turn moving the slide 479, lever 481 and latch 478. This does not result in the release of frame 475, however, since at this time locking cam 476 operates to hold the frame depressed until slide 55 479 is released and the latch reengaged. Cam 476 has a lost motion connection with its supporting shaft, similar to the lost motion connection of non-repeat cam 56, so that these two cams operate in unison, in either 60 direction of rotation.

I claim:

1. In a register having keyboard mechanism comprising a series of members adapted to be set differentially in accordance with 65 an amount to be registered, means for hold-

ing said members in set position, and means for registering in accordance with the amount set; releasing means operable in the setting of any one of said members to disengage the holding means, and means operable 70 by the registering means for placing the releasing means in operative condition.

2. In a register having keyboard mechanism comprising a series of member adapted to be set differentially in accordance with 75 an amount to be registered, means for holding said members in set position, and means for registering in accordance with the amount set; spring-actuated releasing means operable in the setting of any one of said members to disengage the holding means, and means operable by the registering means to energize the releasing means for placing the releasing means in operative condition. 80

3. In a register having keyboard mechanism comprising a plurality of series of keys settable selectively in accordance with an amount to be registered, means for holding said keys in set position, and registering means settable by said keys; spring-actuated 85 releasing means operable to disengage the holding means, a latch adapted to restrain the releasing means, means operable upon setting movement of any one of said keys to release said latch, and means operable by the registering means to retension and latch the releasing means. 90

4. In a register having keyboard mechanism comprising a plurality of rows of keys settable selectively in accordance with an amount to be registered, a locking bail related to each said row and adapted to hold a key in set position, and registering means settable by said keys; releasing means including a spring-actuated member and a 100 member movable thereby and contacting with the locking bails, a latch for said spring-actuated member, a member engaged by said locking bails and operatively related to said latch, and means operable by the 105 registering means to retension and latch the spring-actuated member. 110

5. In a register having keyboard mechanism comprising a plurality of series of keys settable selectively in accordance with an amount to be registered, means for holding said keys in set position, an index member related to each series and adjustable to display a numeral corresponding to the set key, registering means settable by said keys, and means operable by the registering means to release the holding means; means operable by the registering means to lock the index members in adjusted position, and means operable upon setting movement of any one of 120 said keys to release the locking means. 125

6. In a register having keyboard mechanism comprising a plurality of series of keys settable selectively in accordance with an amount to be registered, means for holding 130

said keys in set position, an index member related to each series and adjustable to display a numeral corresponding to the set key, registering means settable by said keys, 5 and means operable by the registering means to release the holding means; means operable by the registering means to lock the index members in adjusted position, a spring operable to release the locking means, a latch 10 adapted to hold said locking means in active position, and means operable upon setting movement of any one of said keys to release said latch.

Signed at Orange, in the county of Essex 15 and State of New Jersey, this 6th day of October, A. D. 1931.

STUART HILDER.
